UNITED STATES PATENT OFFICE

GLENN E. EDMUNDS, OF COLUMBUS, OHIO, ASSIGNOR TO THE BONNEY-FLOYD COMPANY,
OF COLUMBUS, OHIO, A CORPORATION OF OHIO

COMBINATION SPRING BUMPER AND DRAWBAR

Application filed April 21, 1928. Serial No. 271,842.

This invention relates to mine cars, and more particularly to mine cars of the type having the lading bottom arranged below the tops of the axles. Mine cars of this general type are disclosed, for example, in my Patent 1,644,010, granted October 4, 1927.

An object of the invention is to provide an improved bumper and drawbar construction, particularly useful with a car of this type, although adaptable to mine and industrial cars generally.

Another object of the invention is to provide a bumper and drawbar mechanism which may be readily applied to a car with little or no change in its body construction.

Mine cars are ordinarily provided with a rigidly attached bumper at each end, the bumper sometimes being connected by a drawbar extending longitudinally and centrally of the car. Suitable coupling mechanism is attached to each bumper so that the draft is transmitted from one bumper to the other through the drawbar connection. The present invention seeks to provide a yielding bumper construction which will reduce the strain upon the car and take up blows and shocks through a yielding mechanism interposed between the bumper and the fixed parts of the car. The invention seeks to reduce the strains resulting from the draft or pulling action as well as from the pushing or bumping of one car by another.

It will be understood that although the invention is described and claimed as embodied in a mine car, this term is used as covering generally any type of industrial car for work in mines and industrial plants.

Referring to the drawings, wherein there is shown a preferred embodiment of the invention,

Figure 1 is a bottom plan view.

Figure 2 is a side elevational view.

Figure 3 is an end elevational view.

Figure 4 is a fragmentary top plan with parts broken away.

Figure 5 is a fragmentary side elevational view.

Figure 6 is an end view partly in elevation and partly in section.

Figure 7 is a cross sectional view on the line 7—7 of Figure 4.

Figure 8 is a perspective showing one of the bumper supporting brackets attached to the car bottom frame.

Figure 9 is a fragmentary perspective of one end of the bumper with a part broken away.

Figure 10 is a rear elevational view of a portion of the bumper.

Referring to the drawings for a more detailed description, the mine car illustrated comprises a truck having at each side inner and outer sill bars 10, 11 connected by cross girts 12, the latter being arranged in the same horizontal plane with inwardly extending floor or bottom supporting tongues 12' formed on the inner sill bars 10. The lading bottom is substantially the same in construction as that illustrated in my Patent 1,644,010, October 4, 1927, and comprises floor sheets 13 resting upon the cross girts 12, and the truck sill tongues 12', it being noted that the bottom is arranged below the planes of the tops of the axles 14. Above the truck sill bars are arranged laterally extending elevated floor portions formed by the sheets 13', the wheels being covered by suitable hoods 14'. The floor includes a suitable bottom frame, as shown clearly in Figure 6 of my patent above mentioned; the frame comprises upper angle bars 15 and lower angle bars 16, the upper bars having outwardly directed flanges 15' and the lower bars inwardly directed flanges 16', and the bars being connected by vertical webs 17 so as to form vertical side walls of the centrally depressed bottom. Since the formation of this bottom frame is clearly described in my patent, above mentioned, and constitutes no part of the present invention, further description herein is unnecessary.

Referring to the bumper mounting, each bumper 18 is supported adjacent its ends by means of a bracket 19 which has a vertically disposed web 20 adapted to be riveted or otherwise secured through openings 21 to the vertical web 17 connecting the angle bars 15, 16. At its lower end, each bracket has an inwardly directed ledge or flange 22 arranged

in substantially the same horizontal plane pling mechanism, such as that shown in my with the inwardly directed flange 16' of the copending application, Serial No. 210,244, angle 16 whereby to serve substantially as a support for the floor sheet 13. As illustrated 5 in Fig. 7, the inwardly directed flange 16' is cut away a distance from the end of web 17 so that the flange 22 of bracket 19 may be arranged substantially as an extension of the angle bar flange 16' and thus support the 10 bottom 13. At its upper end each bracket has an outwardly directed shoulder 24 which serves as an extension of outwardly directed flange 15' of the bottom-frame angle bar 15. Thus, each bracket is supported by the 15 bottom frame of the car and affords an extension, so to speak, of this frame to support the floor sheets 13, which are supported between the inwardly directed flanges 22 of the brackets at each end.

20 An outwardly tongue 25 serves with tongue 24 as an end support for the elevated floor sheets 13' which are disposed in the plane of the tops of the sill bars (Fig. 1) and thus the brackets are fixedly secured to the floor frame

25 and to the floor sheets, and become practically a unit of the floor frame construction. Each bracket has an integrally formed cylindrical housing 26, which is adapted to receive therein a spring 27 abutting the rear wall 29

30 of the housing. Drawbars 30 extend from end to end of the car through the housing and through the springs, the bars projecting at their ends through openings in fixed walls 31 upon the bumpers. The bumpers have rear-

35 wardly extending side walls 32 (Figure 6) shaped to conform to the webs 19 of the brackets. The side walls 32 extend downwardly and have their lower edges 32' spaced slightly above the floor sheets 13. Just above a slightly curved intermediate portion 33 the bumper

40 walls 32 are directed laterally to form a shoulder 34 spaced below a horizontally and outwardly directed web 35. The shoulder 34 and web 35 form a way to receive an inwardly directed tongue 36 upon the bracket, the tongue serving as a guide for the bumper as it slides upon the bracket. It will be observed that the tongue 36 is spaced vertically above the floor supporting flanges 24, 25 so that as the bumper moves the edges of the web 35 on the bumper will not engage the floor sheets but will be free to pass thereover.

45 Each drawbar 30 has an end nut 30' by means of which the drawbars are connected to the bumpers. These nuts may be employed to initially place the springs 27 under compression, but will be adjusted so that the fixed walls 31 on each bumper are spaced from the ends of the spring housings 26. Whenever a 50 bumper is pressed toward the supporting brackets, the springs will be placed under compression and thus take up the blows which otherwise would be transmitted to the car frame and truck. As will be understood, 55 each bumper is provided with suitable cou-

filed August 3, 1927, and as will be clear from the foregoing, the draft applied to the bumper at either end of the car will be transmitted 70 through the drawbars 30 to the opposite end. Consequently, all pulling strain applied at one end of the car will be transmitted to the opposite end and converted to a pulling pressure on the rear end of the car. 75

As will be observed, each of the drawbars 30 is disposed outside the body of the car and extends through openings 38 formed in the laterally directed flanges upon the inner truck side sill castings 10. The pulling action upon these drawbars is at all times transmitted in the plane of the truck and any lateral or torsional strain is applied to the truck instead of to the body thereabove. 80

85 Due to the simplicity of the construction, it may be readily applied to a mine car in place of the rigid type of bumper. It is simply necessary to attach the supporting brackets and connect the bumpers which are slidably fitted on the brackets by means of the drawbars. Although the drawbars are shown as extending through the truck sill castings, it will be understood that the invention is not limited to this particular arrangement, and that the drawbars may be located in other 90 positions, for instance, within the car body, if desired. However, by locating the drawbars outside the body, the load will not interfere with their operation, and they are readily accessible for adjustment or replacement. 95

100 Obviously, the invention is not limited to the precise construction illustrated and described, since numerous modifications may be made therein without departing from the invention, which is defined in the following 105 claims.

I claim:—

1. In a mine car, a pair of end bumpers, a bumper supporting bracket fixedly positioned on the car adjacent each end of and adapted to directly support a bumper, said brackets and bumper having slidably interfitting parts adapted to guide the bumper, springs interposed between fixed parts of the bumper and brackets for limiting movement of the bumper toward the brackets, spring means for limiting movement of the bumper away from the brackets, rigid stop means operative upon over-compression of either of said spring means to limit positively movement of the bumper, each of said brackets comprising a casting having an integral spring housing and top and bottom floor supporting webs laterally directed and connected by a body web, said bumpers and brackets being disposed at both ends of the car and bars extending longitudinally of the car connecting the bumpers. 115

120 2. In a railway car, an end bumper extending transversely thereof, a pair of spaced 125

supporting brackets fixed to the car and including spring barrels, compression springs mounted therein, vertical web portions extending from said barrels and terminating in floor supporting flanges, and said bumper having ends which slidably engage said barrels and web portions in guiding said bumper.

3. In a railway car, an end bumper extending transversely thereof, a pair of spaced supporting brackets fixed to the car and including spring barrels, compression springs mounted therein, horizontal floor supporting flanges extending from opposite sides of said brackets, a horizontal guide flange secured to said barrel, and said bumper having ends which slidably engage said spring barrels and having a way slidably engaging with said horizontal guide flange.

4. In a mine car, a bumper, a pair of brackets rigidly secured to the end of the car at opposite sides thereof, said bumper and brackets having rigidly formed thereon slideable interfitting parts forming a fixed guide for the bumper, bars located at opposite sides of the car and extending through the brackets and connected with the bumper.

In testimony whereof I have hereunto set my hand.

GLENN E. EDMUNDS.
